United States Patent Office

Des. 228,598
Patented Oct. 16, 1973

228,598

DISPLAY TRAY OR SIMILAR ARTICLE

Harley H. Mattheis, Verona, N.J., assignor to Ethyl
Development Corporation, Kansas City, Mo.

Filed Jan. 24, 1972, Ser. No. 220,557

Term of patent 14 years

Int. Cl. D6—06

U.S. Cl. D6—132

FIG. 1.

FIG. 2.

FIG. 3.

FIG. 4.

FIG. 5.

FIG. 6.

FIG. 1 is a top, front, perspective view of a display tray or similar article showing my new design;

FIG. 2 is a top plan view thereof;

FIG. 3 is a front elevational view thereof;

FIG. 4 is a side elevational view thereof;

FIG. 5 is a rear elevational view thereof; and

FIG. 6 is a bottom view thereof.

I claim:

The ornamental design for a display tray or similar article, substantially as shown.
